[57] **CLAIM**

The ornamental design for a combined disc player and radio receiver, as shown and described.

DESCRIPTION

FIG. 1 is a perspective view of a combined disc player and radio receiver showing our new design;

FIG. 2 is a top plan view thereof;

FIG. 3 is a left side elevational view thereof;

FIG. 4 is a front elevational view thereof;

FIG. 5 is a bottom plan view thereof;

FIG. 6 is a right side elevational view thereof; and

FIG. 7 is a rear elevational view thereof; and,

FIG. 8 is a perspective view thereof, wherein the panel portion is in the open position; the undisclosed inside portions of the combined disc player and radio receiver form no part of the claimed design.

The broken line showing of the inside of the combined disc and radio receiver is for illustrative purposes only and forms no part of the claimed design.
